UNITED STATES PATENT OFFICE

J CLARENCE McCARTHY, OF LANCASTER, PENNSYLVANIA, ASSIGNOR TO ARMSTRONG CORK COMPANY, OF LANCASTER, PENNSYLVANIA, A CORPORATION OF PENNSYLVANIA

SURFACE DECORATION

Application filed May 28, 1927. Serial No. 194,936.

This invention relates to surface decoration, and more particularly to the decoration of a flexible surface covering, such, for example, as the hard surfaced floor coverings, like linoleum or felt base goods, or wall coverings, which are made in sheet form, to be applied over a wall or floor.

The decoration is made to simulate the irregular color effects of ceramic tiling, travertin and marble, such as the tile commonly known as Dutch tile. Such tiles do not have a uniform color, but have a considerable variation in color, or shades of color, on the individual tile.

15 In the accompanying drawings, illustrating certain preferred embodiments of my invention

Figure 1 shows my surface decoration applied to a piece of linoleum;

20 Figure 2 is a top plan view showing the layers of paint applied to the linoleum;

Figure 3 is a sectional view on the line III—III of Figure 2; and

25 Figure 4 shows a modified method of applying the paint.

Referring to Figure 1, there is shown a surface decoration applied to a piece of embossed linoleum. In forming this surface decoration, the linoleum 2 is first embossed, 20 and is then given a ground coat 3 of paint (Figures 2 and 3). Successive layers of paint, 4, 5 and 6, preferably shades of the same color, are then applied over the ground coat 3. A top coat 7 is applied over the last 25 coat 6 of the coats 4, 5 and 6 which are shades of the same color, the top or last coat 7 being preferably the same shade as the ground coat 3. In simulating tiling, I prefer that the ground coat 3 and the top coat 7 be of the same color and be a color which may represent mortar between the tiles. The intermediate shades 4, 5 and 6 which are of the same color preferably, may be any color ordinarily used in tiling, such as red.

45 The irregular mottled effect of haphazardly intermingled colors and shades of color shown in Figure 1, is preferably obtained by grinding or abrading the painted surface, as by passing the painted linoleum through an 50 abrading machine which grinds off the paint.

The last or top coat 7 will probably all be removed except where it lies in depressions or embossed portions below the general plane of the decorated surface. The underlying colors will be brought to the surface in irregular patches with shaded edges gradually merging into different shades or colors. The irregularities naturally occurring in the thickness of the linoleum will cause the grinding to remove the paint coatings irregularly 55 so that an irregular effect will be produced which will not be repeated in any portion of the decorated surface. The irregularly distributed shades of the several coats, applied intermediate the ground and top coats, gives 60 the appearance of ceramic tiling in which varying shades appear by reason of irregularities in firing.

The top coat 7 is preferably a color which will simulate mortar, for this color will be 65 left in the embossed portions between the tiles. The ground coat 3 is applied to give the decoration sufficient body that the abrading process will not cut through to the linoleum. If the abrasion proceeds through the 70 intermediate coats to the ground coat, and the ground coat is the same color as the mortar, the appearance is that of tiling in which small pits or depressions have occurred and are filled with mortar.

75 It will be understood that the thickness of the several coats of paint may not be more than a few thousandths of an inch, but the thickness of the sections in Figure 3 has been greatly enlarged in order to bring out the 80 nature of the decoration.

Figure 4 shows a modified process in which several shades or several colors are applied irregularly over the surface, instead of complete coats of paint being applied over the 85 decorated surface. For example, the ground color 3' is applied as an even coat to give a base on which variegated colors are applied. The last coat 7' covers up the variegated colors and forms the color of the interliners 90 between the tile. The colors 4', 5' and 6' are irregularly distributed over the ground coat 3' by means of an air brush or by daubing or dropping on spots of paint. A flexible covering coated in accordance with the method just 95

described, is abraded in the same manner as the decoration illustrated in Figures 2 and 3 and the results are substantially the same. The variegated colors or shades of the same color appear as irregular patches on the surface, merging into one another and producing an irregular effect which is not repeated in any portion of the decoration, due to the inherent slight irregularities in the thickness of the linoleum which are sufficient to render the abrasion uneven, and to the irregular occurrence of the paints having different color characteristics.

The method illustrated in Figure 4 is applicable to flexible coverings made in sheet form, since they may be run through an abrading machine and the irregular application of paint will necessarily produce a decoration having no fixed color pattern, even though the abrading and painting be done with machine regularity. The abrading may be done by hand, however, if desired. The irregular thickness of the material will be sufficient to bring out irregular areas of different colors and shades of color because the coats of paint are of comparatively slight thickness.

The paints applied are preferably colored lacquers, such as nitrocellulose lacquers, which may be applied as a spray with an air brush. By this procedure I may produce a uniform distribution over an embossed surface without filling up the depressions. I may also provide patches of color varying in intensity, or intermingled colors. The process, involving applying a top coat the color of the mortar, and abrading the surface to bring out various colors or shades of color, is particularly effective in producing a tile pattern in which the mortar colored paint substantially coincides with the mortar joint depressions. If an attempt were made to print embossed linoleum, difficulty would be encountered in laying the paint into the depressions so that the mortar color would exactly match the depressed portions. By applying the last coating over the whole surface and then abrading it off, the mortar colored paint coincides exactly with the depressions.

The surface of the material is not necessarily embossed. The irregular color effect may be obtained by applying the coats of paint or patches of paint to a plane surface and grinding it through. After grinding, if desired, interliners may be printed on the coating.

If the decoration is to be applied to felt base material, the colors may be applied first and the material may then be embossed, after which the grinding operation is performed, resulting in the depressed interliners having a layer of paint in the color of the last coating applied while the raised portions of the

surface are given an irregular appearance, due to the grinding.

The invention is particularly adapted for the production of the variegated surface effect of Dutch tiling by means of applying the paints and then abrading away part of the paint. The abrading takes place irregularly because of the irregular thickness of the sheet material so that each tile-like space will have an irregular color effect which differs from that of any other tile-like space. The decorated sheets will be different because the grinding will bring out irregularly the different paint coatings, merging one into another.

Although nitrocellulose type of lacquers are preferred because of their quick drying properties, oil paints may be used. It will be understood also that while the colors are preferably sprayed to produce merging patches of color, or even coatings upon plain or depressed surfaces, the paints may be applied with any ordinary type of coating machine.

The effect of glazed tiling may be obtained by giving the decorated surface a coat of clear transparent lacquer. The wearing qualities of the surface may be improved somewhat if such a lacquer be applied to a decorated floor cover. The decoration may be applied to a flexible covering not intended to be subjected to much wear by using paints or lacquers in comparatively thin coats. If the decoration is applied to a linoleum or felt base, or other hard surfaced floor covering, the ground coat will prevent the linoleum from showing through in the event that the colored intermediate layers are worn through. A coat of clear lacquer over the decorated floor covering will extend the life of the decoration and minimize the effects of scuffing, particularly on those portions of the decoration where the abrading has extended to the ground coat.

The word paint, as used herein, is intended to be a term of general description and not of limitation, and is intended to include color paints of the lacquer type.

My process is applicable to various types of flexible coverings and may be used to produce variegated color effects thereon. The process has been described with particular reference to an embossed linoleum, simulating tiling, but it will be understood that various sheet goods to be applied to walls or floors may be decorated according to my process, with or without embossing.

While I have illustrated and described certain preferred embodiments of my invention, it will be understood that the invention is not limited thereto, but may be otherwise practiced and embodied within the scope of the following claims.

I claim:

1. The process of decorating a flexible sur-

face covering of the felt-base-linoleum type which consists in applying superimposed layers of paint to the surface and abrading the paint to expose portions of layers of paint below the top layer.

2. The process of decorating a flexible surface covering which consists in embossing the covering, applying a ground coat of paint to the entire surface of the covering, making 10 applications of paints having different color characteristics over the ground coat, applying a top coat of paint and abrading the surface to remove the top coat and portions of the under coats the portions of the top coat lying within the embossed portions being left intact.

3. The process of decorating a flexible surface covering which consists in embossing the covering, applying a ground coat of paint to 20 the surface of the covering, applying successive coats of paint having different color characteristics, applying a top coat of paint, and abrading the paint to remove the top coat from the unembossed portions and expose the intermediate layers of paint in haphazard variegations.

4. The method of decorating a flexible surface covering which consists in embossing the covering, applying irregular patches of 30 paints having different color characteristics thereon, applying a top coat, and abrading the paint to remove the top coat from the unembossed portions and irregularly expose portions of the colored patches.

35 5. The method of decorating a flexible surface covering which consists in making superposed applications of paints having different color characteristics, and abrading the paint irregularly to produce a haphazard variegated colored decoration.

40 6. The method of decorating a flexible surface covering which consists in making superposed applications of paints having different color characteristics, abrading the paint irregularly to produce a haphazard variegated color decoration, and applying a coat of transparent lacquer over the colored surface thus produced.

45 7. A flexible surface covering of the felt-base-linoleum type comprising a base having superposed paint layers extending over a substantial area of the covering, at least one paint coat being discontinuous and being thinned at its edges so as to present an irregular margin whereby a lower paint layer is exposed in an irregular fashion.

50 8. A flexible surface covering of the felt-base-linoleum type comprising a base having superposed paint layers, the material being 60 embossed and paint extending into the embossed portions, at least one paint coat being discontinuous and having its edge portions thinned and terminating in irregular margins so as to expose a lower paint layer in an irregular fashion, the paint in said embossed

portions being substantially continuous therein.

9. A flexible floor covering comprising a base material of the felt base-linoleum type and having the irregularities of thickness inherent in said materials, said base material having superposed paint layers over the base, a paint layer having its margins of irregular conformation and corresponding generally to irregularities in thickness in the base material, an underlying paint coat being thus irregularly exposed.

10. The process of decorating a floor covering of the felt base-linoleum type having the surface irregularities inherent in such materials, which comprises making superposed applications of paints having different color characteristics, and removing paint at the high portions of the surface irregularities so as to locally expose the underlying paint 85 coats.

11. The process of decorating hard surface flexible floor coverings, which consists in embossing the floor covering, applying superposed coats of paint having different color characteristics, and so removing paint at the unembossed portions as to expose the undercoats of paint while leaving the paint in the embossed portions substantially intact.

12. The process of decorating hard surface 25 flexible floor coverings, which comprises making superposed applications of paints having different color characteristics, and removing paint irregularly so as to produce a haphazard variegated colored decoration.

In testimony whereof I have hereunto set my hand.

J CLARENCE McCARTHY.
